CLAIM

The ornamental design for a helmet, as shown and described.

DESCRIPTION

FIG. 1 is a left side view of a helmet showing our design;

FIG. 2 is a front view thereof;

FIG. 3 is a rear view thereof;

FIG. 4 is a top view thereof;

FIG. 5 is an inside view thereof;

FIG. 6 is a front right perspective view thereof; and,

FIG. 7 is a rear right perspective view thereof.

The broken lines illustrate portions of the helmet that form no part of the claimed design.
